UNITED STATES PATENT OFFICE.

ASAPH MERIAM HIGLEY, OF CUMMINGS, KANSAS.

DRAG-SAW.

1,131,239.

Specification of Letters Patent.

Patented Mar. 9, 1915.

Application filed March 11, 1914. Serial No. 824,010.

To all whom it may concern:

Be it known that I, ASAPH M. HIGLEY, a citizen of the United States, residing at Cummings, in the county of Atchison and 5 State of Kansas, have invented certain new and useful Improvements in Drag-Saws; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in drag saws and the object in view is to produce a simple and efficient device of this nature so arranged that the log or other article to be sawed may be gripped and securely held while the saw is 20 operated.

Another feature of the invention comprises a drag saw in which an auxiliary handle may be attached to the apparatus so 25 that the saw may cut in a horizontal position.

The invention comprises various details of construction and combinations and arrangements of parts which will be hereinafter 30 fully described, shown in the accompanying drawings and then specifically defined in the appended claim.

I illustrate my invention in the accompanying drawings, in which:

35 Figure 1 is a perspective view of my improved drag saw. Fig. 2 is a side elevation, and Fig. 3 is a perspective view showing the adjustment of the parts to enable the saw to be operated in a horizontal plane.

40 Reference now being had to the details of the drawings by letter, A designates the drag saw having a plate B secured thereto from which projects a pin C. The operating lever is designated by letter D and is 45 pivotally connected through the medium of the pin D' with the bars E which are fastened to said plate B, one upon each side of the lever. The lever D has a pin F projecting from one side thereof, forming a handle 50 which, together with the handle C, may be utilized for adjusting the saw or starting the same as an operator commences to cut a log or other article.

55 A bar, designated by letter H, is pivotally connected to the lever and telescopes within

a shell I which carries a grooved anti-friction roller, adapted to rest upon the rear edge of the saw. Said bar H may be held within different adjusted positions within the shell and the rear end of said bar has a 60 spring O bearing against the same, while its other end engages the handle, said spring being provided for the purpose of holding said roller upon the rear edge of the saw, as will be readily understood, to guide the latter and press down upon the saw while it is in operation.

A bar R has pivotal connection through the medium of the pivot R' with the lever D and said bar carries pins X' and T' upon 70 which the bar T⁴ is mounted. A lever X is pivotally mounted upon the pin X' and the gripping jaws T are mounted upon the pivotal pin T', while a third gripping jaw S is pivotally mounted upon a pin T² carried by 75 the bar T⁴. Springs X² are fastened at corresponding ends to the upper ends of the jaws T, while their other ends are fastened to the lever X upon opposite sides thereof. Projecting from the edge of one of the jaws 80 T is a lug T³, shown clearly in dotted lines in Fig. 2 of the drawings, and to which the links S' are pivotally connected which in turn are pivotally connected to the upper end of the shank portion of the gripping 85 jaw S.

A toothed segment W is fastened to the bar R, the teeth of which are adapted to be engaged by the edge of the lever X to hold the various gripping members in or out of 90 engagement with the log or other article being sawed.

In the modified form of saw, in which it is held in a horizontal position and is illustrated in the drawings, an auxiliary handle 95 J is used which has a shank portion L, the ends of which are bent laterally as at L' and adapted to be held by means of bolts L² to the lever D, as shown.

In applying the device, the operator places 100 the pointed ends of the gripping jaws in contact with the log and, by pulling upon the lever X putting the springs X² under tension, the points at the ends of the jaws T may be caused to penetrate the log and, as 105 the shank portion of the jaw carrying the lug T³ tilts upon its pivot, the toggle link connection intermediate the same and the upper end of the shank portion of the jaw S will cause the point upon the latter to en- 110

gage the log in the manner shown in Fig. 1 of the drawings, thus securely gripping and holding the frame upon the log. It will be understood that the springs X^2 are of sufficient strength to cause this gripping action when the lever is swung in the manner described.

By the provision of a drag saw made in accordance with my invention, it will be noted that a simple and efficient device is afforded whereby an article being sawed may be securely gripped by the members shown while the saw is operated to cut the log or other article, the grooved pulley riding upon the upper edge of the saw serving as a means for guiding the same and causing a slight pressure upon the saw, sufficient to effect the sawing.

When it is desired to adapt the saw to cut in a horizontal plane, the auxiliary handle is attached as shown in the drawings, there-

by affording convenient means for reciprocating the saw.

What I claim to be new is:—

A drag saw apparatus comprising a bar, a saw and means for reciprocating the latter, a lever pivotally mounted upon the bar, gripping jaws arranged side by side and pivotally mounted upon the bar, brackets projecting from the opposite sides of the lever, springs secured to the upper portions of the shanks of said gripping jaws, the shank of one of said jaws having a lug thereon, a third gripping jaw pivotally mounted upon the bar and links pivotally connecting the upper end thereof with said lug, as set forth.

In testimony whereof I hereunto affix my signature in presence of two witnesses.

ASAPH MERIAM HIGLEY.

Witnesses:

M. J. LAIRD,
ROBERT G. WALKER.
